[57] CLAIM

I claim the ornamental design for a wheel and edge-cleaning brush attachment for vacuums, as shown and described.

DESCRIPTION

FIG. 1 is an isometric view of a wheel and edge-cleaning brush attachment for vacuums showing new design;
FIG. 2 is a bottom plan view thereof;
FIG. 3 is a top plan view thereof;
FIG. 4 is a front elevation view thereof;
FIG. 5 is a rear elevation view thereof;
FIG. 6 is left side elevation view thereof; and,
FIG. 7 is a right side elevation view thereof.
